UNITED STATES PATENT OFFICE.

JACOB KAPPLER, OF PHILADELPHIA, PENNSYLVANIA, ASSIGNOR TO GILL & COMPANY, OF PHILADELPHIA, PENNSYLVANIA, A CORPORATION OF PENNSYLVANIA.

DESIGN FOR A LAMP-SHADE.

40,624.

Specification for Design.

Patented Apr. 12, 1910.

Application filed July 17, 1909. Serial No. 508,246. Term of patent 7 years.

To all whom it may concern:

Be it known that I, JACOB KAPPLER, a citizen of the United States, residing at Philadelphia, in the county of Philadelphia, State of Pennsylvania, have invented a new, original, and ornamental Design for a Lamp-Shade, of which the following is a specification, reference being had to the accompanying drawing, forming part thereof.

Figure 1 is a side view in elevation of a lamp shade showing my new design. Fig. 2 is a top plan view of the same.

The design consists in a shade having a rectangular lower edge portion with vertical prism surfaces; a circular shaped collar; and the portion between the collar and the lower

edge portion of the shape of a truncated rectangular pyramid with oblique concave prism surfaces; the corners or angles of the lower edge portion and the corners or angles of the truncated portion having plain convex surfaces in contrast with the sharp angles of the prism surfaces between the corners.

I claim:

The ornamental design for a lamp shade, as shown and described.

JACOB KAPPLER.
